United States Patent Office.

P. J. CLARK, OF WEST MERIDEN, CONNECTICUT.

Letters Patent No. 78,058, dated May 19, 1868.

IMPROVEMENT IN LANTERNS.

The Schedule referred to in these Letters Patent and making part of the same.

TO ALL WHOM IT MAY CONCERN:

Be it known that I, P. J. CLARK, of West Meriden, in the county of New Haven, and State of Connecticut, have invented a new and improved Lantern; and I do hereby declare that the following is a full, clear, and exact description thereof, which will enable others skilled in the art to make and use the same, reference being had to the accompanying drawings, forming a part of this specification.

This invention relates to a new and improved application of guards to a lantern, as hereinafter fully shown and described, whereby several advantages are obtained, which will be hereinafter set forth.

In the accompanying sheet of drawings—

Figure 1 is a vertical central section of my invention, taken in the line *x x*, fig. 2.

Figure 2 a horizontal section of the same, taken in the line *y y*, fig. 1.

Similar letters of reference indicate corresponding parts.

A represents the glass globe of a lantern, B the metal cap, C the metal base at the lower part of the lantern, and D^X the lamp, fitted within the base, and secured by any proper fastenings, *a a*.

The upper edge of the base, C, is turned over and outward, to form a flange, *b*, at right angles to the body or main portion of the base, as shown clearly in fig. 1, and this flange has two notches, *c c*, made in it, at opposite points, as shown clearly in fig. 2.

D represents the guards of the lantern, which are constructed of wire, as usual, and have their upper ends fitted in the cap B. The lower ends of the guards pass through a ring, E, of sheet metal, bent so as to be convex on its upper surface and concave at its under surface, as shown in fig. 1. The lower ends of two of the guards D, below the ring E, are bent or curved, in such a manner as to form shoulders, *d*, for the flange *b* to catch over, and it will be seen that, by placing the flange *b* in contact with the ring E, so that the ends of the guards which have the shoulders *d* on them may pass through the notches *c c* in the flange *b*, and then turning the base, C, the flange *b* will catch over the shoulders *d d*, and the bar be firmly connected to the ring, and all the parts of the lantern firmly connected together.

A spring-catch, F, is attached to the under side of the flange *b*, which engages with the lower end of one of the guards D, and prevents the base, C, from casually turning.

By this arrangement the guards, as well as the base, are secured in position or firmly connected together, and all the parts firmly connected, and at the same time the globe A may be readily attached, when necessary, for cleaning or other purposes, and in case of the breaking of a globe, a new one may be applied without any trouble or difficulty whatever.

Having described my invention, I claim as new, and desire to secure by Letters Patent—

1. The ring E, formed as shown, with the lower ends of the guards D passing through it, and two or more of said guards provided with shoulders *d*, in combination with the flange *b* on the upper edge of the base, C, with notches *c c* made in it, all arranged substantially as and for the purpose set forth.

2. I further claim the spring-catch F attached to the under side of the flange *b*, when said spring-catch is used in connection with the ring E and guards D, and all constructed and arranged as set forth.

The above specification of my invention signed by me, this 7th day of March, 1868.

P. J. CLARK.
